US00D617642S

(12) **United States Design Patent**
Jonzon et al.

(10) **Patent No.:** **US D617,642 S**
(45) **Date of Patent:** ** *Jun. 15, 2010

(54) **SECONDARY PACKING MATERIAL**

(75) Inventors: **Anders Jonzon**, Raa (SE); **Jacob Volckerts**, Helsingborg (SE); **Jörgen Ingvarsson**, Ängelholm (SE); **Mikael Lars Johan Petersson**, Helsingborg (SE)

(73) Assignee: **Wellplast AB**, Munka-Ljungby (SE)

(*) Notice: This patent is subject to a terminal disclaimer.

(**) Term: **14 Years**

(21) Appl. No.: **29/182,318**

(22) Filed: **May 27, 2003**

(30) **Foreign Application Priority Data**

Nov. 27, 2002 (SE) 02-1708

(51) **LOC (9) CL.** **09-07**

(52) **U.S. CL.** **D9/456**

(58) **Field of Classification Search** D9/434, D9/456; D6/577, 575; 99/445; 428/43, 428/181, 118, 116
